(57) **CLAIM**

The ornamental design for a disposable teeth cleaning system, substantially as shown and described.

DESCRIPTION

FIG. 1 is a front perspective view of a disposable teeth cleaning system;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

The broken lines showing bristles and floss illustrate portions of the teeth cleaning system that form no part of the claimed design.
